UNITED STATES PATENT OFFICE.

HENRY GEISENHÖNER, OF SCHENECTADY, NEW YORK, ASSIGNOR TO THE GENERAL ELECTRIC COMPANY, OF NEW YORK.

DETACHABLE LAMINATED POLE-PIECE FOR DYNAMO-ELECTRIC MACHINES.

SPECIFICATION forming part of Letters Patent No. 596,152, dated December 28, 1897.

Application filed October 11, 1897. Serial No. 654,796. (No model.)

To all whom it may concern:

Be it known that I, HENRY GEISENHÖNER, a citizen of the United States, residing at Schenectady, in the county of Schenectady, State 5 of New York, have invented certain new and useful Improvements in Detachable Laminated Pole-Pieces for Dynamo-Electric Machines, (Case No. 605,) of which the following is a specification.

10 The object of my invention is to provide a detachable laminated pole-piece that is cheap to construct and which requires no particular skill to assemble in position on the machine.

In the accompanying drawings, Figure 1 is 15 a partial side elevation of my improved pole-piece mounted in position on a revolving spider. Fig. 2 is a partial section of the same. Fig. 3 is a sectional detail of the clamping-wedges, taken on line 3 3 of Fig. 1; and Fig.

20 4 is a slight modification.

My invention is shown in connection with a revolving field-magnet structure, where it has the greatest utility; but it can be applied to a stationary field-magnet, if desired.

25 The spider A consists of a hub C, having a number of unconnected arms B with enlarged ends. Surrounding the enlarged ends of the arms is a ring or rim D, forming a support for the pole-pieces. This ring is shrunk in place;

30 but other means of securing it may be employed. Extending across the outer periphery of the rim and parallel to the shaft of the machine are dovetail slots, and in these slots are mounted pole-pieces E. The slots in the 35 rim are preferably made by a milling-cutter, so that they will be counterparts.

Each pole-piece comprises a bundle of laminæ having heavier end plates E' and secured together by bolts extending parallel with the 40 dovetail slots. The outer end of each pole-piece is enlarged. This increases the pole-face and at the same time provides reliable means for retaining the field-coil J against centrifugal action. The inner end of each

45 pole-piece has a dovetail projection E², adapted to fit into a similarly-shaped slot in the rim D. On each side of the dovetail projection are shoulders E³, adapted to rest on rim D and form a part of the support. It is intended

50 that there shall be a good working fit between the pole-pieces and rim, so that the pole-

pieces may be mounted in place without the aid of tools. The iron laminæ of which the poles are composed are preferably counterpart punchings, although the section and 55 shape of certain of them may be varied, if desired. In each of the laminæ are holes for the clamping-bolts F, a hole for wedges H and H', and a slot G, which divides the lower portion of the laminæ into two parts. Preferably the 60 holes and slots in the punchings are made by the same die that forms the main body. By this arrangement all work on the laminæ is done at one operation, thereby reducing the cost and simplifying the construction. I have 65 found that it works very satisfactorily to make slot G with a shearing cutter. Then no material is wasted, and there is practically no air-space between the two lower portions of the pole. For the purpose of illustration slot 70 G has been slightly enlarged; but it is to be understood that it can be any desired width.

Wedges H and H' are formed by dividing a round steel bar into two parts, the line of division extending diagonally from one end to 75 the other. These wedges are adapted to be inserted in the pole-piece from opposite ends and as they are forced together expand the lower part of the pole-piece, causing it to be retained in position by friction between the 80 dovetail projection and side of the slot.

In Fig. 2 a field-coil J is shown in section on a pole-piece, with the insulation and means employed to retain the coil in position clearly illustrated.

85 Fig. 3 shows a sectional view of a dovetail projection in which wedges H and H' are shown in their normal position with the pole-piece expanded.

Fig. 4 shows a slight modification in which 90 two slots G and G' are provided and a set of wedges for each slot.

In assembling the machine a coil J is placed in position on a pole-piece. The dovetail projection of the pole is mounted in a slot in the 95 rim and wedges H and H' driven into place. This slightly expands the lower end of the pole and binds it in place. In a machine having a revolving field-magnet there is comparatively little force tending to move the 100 pole-pieces in a direction parallel to the shaft; but the centrifugal action is more or less

great, depending upon the speed of the machine. The dovetail construction presents many desirable features and has been commonly used; but the means employed in securing the field-poles in position have not been entirely satisfactory. In certain prior constructions wedges have been employed which were located on both sides of the pole between the sides of the core and the rim or support. This necessitated very accurate adjustment. Otherwise one side would be wedged slightly different from the other and the pole-face would be nearer its adjacent pole-face on one side than the other. In other words, it was the wedges which formed the support for the poles and determined their position. To enable the poles to be set up in their proper position, it has been found necessary to separately fit all of the poles, and in taking down a machine for repairs to mark all of the keys and pole-pieces and the place they occupy in the support, so that they may be set up again correctly. By making the dovetail projections of the pole-pieces a working fit with the dovetail slots and providing shoulders which rest on the rim a very slight lateral expansion of the pole will serve to clamp it in place, and the wedges in no way form a support for the poles.

30 What I claim as new, and desire to secure by Letters Patent of the United States, is—

1. In a dynamo-electric machine, the combination of a support provided with slots ex-

tending parallel to the shaft of the machine, laminated detachable pole-pieces having projections inserted in the slots, and means for securing the pole-pieces in place by expanding them at the point where they enter the slots.

2. In a revolving field-magnet structure for dynamo-electric machines, the combination of laminated detachable field-poles having split dovetail projections at one end, a support having dovetail slots extending parallel to the shaft of the machine in which the poles are mounted, and wedges for expanding the dovetail projections of the poles.

3. In a revolving field-magnet structure for dynamo-electric machines, the combination of laminated detachable pole-pieces, each pole-piece being slotted and provided with a dovetail projection at one end and an overhanging portion to retain the field-coil at the other, and bolts for securing the laminae together, a ring or support having dovetail slots in which the pole-pieces are mounted, and a pair of wedges for each pole-piece adapted to be inserted in position from the opposite ends to expand the dovetail portion of the pole.

In witness whereof I have hereunto set my hand this 6th day of October, 1897.

HENRY GEISENIÖNER.
